ANTHONY G. M. MICHELL, OF MELBOURNE, VICTORIA, AUSTRALIA, ASSIGNOR TO
MICHELL-CRANKLESS ENGINES CORPORATION, OF NEW YORK, N. Y., A CORPORATION
OF NEW YORK

CRANKLESS MECHANISM AND METHOD OF MAKING CRANKLESS MECHANISMS

Application filed December 20, 1929. Serial No. 415,386.

This invention relates to crankless mechanisms and particularly to reciprocating units therefor and to a method of making such units.

5 An example of a crankless mechanism to which the present invention relates is illustrated in applicant's Reissue Patent No. 15,756 granted February 5, 1924.

The reciprocating units of crankless mechanism constructed according to the patent above mentioned comprise either one or two pistons, together with two slipper elements making working engagement between the piston or pistons and a rotating slant or swash 15 plate, and a yoke or bridge member which connects the piston or pistons with the supporting means of the slipper elements. The present invention relates to the piston structure, the yoke or bridge member and to the 20 supporting means of the slipper elements.

The invention has for its salient object to provide a reciprocating unit for mechanism of the character specified so constructed that the unit will be light in weight but will be 25 strong and rigid in construction.

Another object of the invention is to provide a reciprocating unit so constructed that it can be economically manufactured.

Further objects of the invention will appear from the following specification taken 30 in connection with the drawings which form a part of this application, and in which

Fig. 1 is a longitudinal view partly in section and partly in elevation of a reciprocating unit constructed in accordance with the 35 invention;

Fig. 2 is a transverse sectional elevation taken substantially on line 2—2 of Fig. 1;

Fig. 3 is a plan view of one of the disks on 40 which the slipper pad is mounted;

Fig. 4 is an elevational view illustrating the method of making the unit;

Fig. 5 is a longitudinal sectional elevation similar to Fig. 1 but showing a slightly 45 modified form of construction; and

Fig. 6 is a transverse sectional elevation taken substantially on line 6—6 of Fig. 5.

The invention briefly described consists of 50 a reciprocating unit for crankless mechanism comprising and formed from a tubu-

lar member and of a method of making a reciprocating unit from tubular stock. Disks or heads are secured to the ends of the tubular member and with the end portions of the member form pistons. The intermediate portion of the tubular member is recessed or cut away and provided with a longitudinal slot formed by oppositely extending walls for receiving studs or tails carried by the slipper pads.

55 Further details of the invention will appear from the following description.

The reciprocating unit is formed from an elongated member 10 of tubular stock preferably of steel. The ends of the tubular member 10 have secured thereto in any suitable manner as by screwing or welding heads 11 which form with the end portions of the tubular member pistons.

60 The central portion of the tubular member is recessed or cut away to receive the peripheral portion of the swash plate. This may be done by cutting transverse notches 12, 12. A longitudinal cut is then made approximately on the line indicated as X in Fig. 4 thus removing the portion of the tubular member between the notches and below the line X. The remaining portions of the 65 walls of the tubular member disposed between the notches 12, 12 are then bent inwardly as shown in Fig. 2, the inner edges 13, 13 of the walls or flanges 14 being spaced apart to form a longitudinal slot, the purpose of which will be hereinafter described.

70 The end portions of the tubular member forming the pistons and disposed outwardly from the notches 12, 12 are closed by disks 15, 15 which may be secured in any suitable manner as by welding, the welded joints being shown at W. The disks are preferably 75 provided with centrally disposed openings 16 within which are secured bosses 17 having spherical seats or sockets 18 which receive spherical bearing surfaces 19 of slipper pads 20. The opposite surfaces 21 of the pads are 80 flat and engage the sides of the swash plate 22.

85 Each of the slipper pads 20 has projecting therefrom a stud or tail pin 25, the tail pins being disposed in the slot formed between 90

- the ends 13 of the bent in portions or flanges 14 and being guided thereby. The tail pins 25 may be tubular or hollow in construction for lightness, if desired.
- 5 The inner ends 13, 13 of the walls or flanges 14, 14 may, if desired, extend toward each other for a portion of their length a sufficient distance to meet, the meeting parts being welded to increase the strength and 10 rigidity of the yoke.
- In the modified form of construction illustrated in Figs. 5 and 6 the ends of the tubular member 30 are screw threaded to receive the piston heads. The member 30 is notched 15 and cut away in the manner shown in Figs. 1 and 4 but the walls of the tubular member between the notches instead of being bent inwardly as shown in Fig. 2 are bent outwardly as shown in Fig. 6 to form flanges 31.
- 20 An insert preferably formed of forged steel is secured within the recessed or cut away portion of the tubular member and comprises end walls or plates 32, 32 and a longitudinally extending curved connecting 25 wall 33. The wall 33 extends laterally from the tubular member and is secured at its outer edges to the flanges 31 as shown in Fig. 6. The insert is preferably secured in place by welding as shown at W.
- 30 The slipper bearings and sockets for the slippers are secured to the walls or plates 32, 32 in the manner shown in Fig. 2. The flanges 31, 31 may be machined to form bearings for guide slippers 35 which are pivoted 35 or otherwise cammed by the frame of the machine and act to prevent rotation of the reciprocating member about its longitudinal axis.
- From the foregoing description it will be 40 evident that a simple, practical and relative light reciprocating unit has been designed and furthermore, that the structure will be stiff and rugged. Also, it will be noted that a simple, practical and inexpensive method of making reciprocating units from tubular stock has been worked out.
- 45 Although certain specific embodiments of the invention have been particularly shown and described, it will be understood that the 50 invention is capable of modification and that changes in the construction and in the arrangement of the various cooperating parts may be made without departing from the spirit or scope of the invention, as expressed 55 in the following claims.
- What I claim is:
1. A method of making a reciprocating unit for crankless mechanisms which consists of utilizing a piece of tubular stock, securing heads to the ends thereof to form pistons, slotting the piece in spaced planes intermediate the ends of the piece, and bending the walls to form a yoke connecting the ends of the piece. 60
- 65 2. A method of making a reciprocating unit for crankless mechanisms which consists of utilizing a piece of tubular stock, 70 securing heads to the ends thereof to form pistons, slotting the piece in spaced planes intermediate the ends of the piece, and bending the walls to form slipper guiding means. 75
3. A method of making a reciprocating unit for crankless mechanisms which consists of utilizing a piece of tubular stock, 80 securing heads to the ends thereof to form pistons, slotting the piece in spaced planes intermediate the ends of the piece, and bending the walls to form a guide slot. 85
4. A reciprocating unit for crankless mechanisms comprising a piece of tubular stock having heads secured to the ends thereof and having its central portion slotted and bent inwardly to form a hollow yoke connecting the ends. 90
5. A reciprocating unit for crankless mechanisms comprising a piece of tubular stock having heads secured to the ends thereof and having its central portion slotted and bent inwardly to form a hollow yoke connecting the ends and to form slipper guiding means. 95
6. A reciprocating unit for crankless mechanisms comprising a piece of tubular stock having heads secured to the ends thereof and having its central portion slotted and bent to form a hollow yoke connecting the ends and to form slipper guiding means, and plates secured in the central slotted portion having slipper bearings thereon. 100
